NILS PETER ERIK ANDERSEN, OF ELM GROVE, WISCONSIN, ASSIGNOR TO HARNISCH-
FEGER CORPORATION, OF MILWAUKEE, WISCONSIN, A CORPORATION OF WISCON-
SIN

CUPOLA CHARGER

Application filed January 5, 1931. Serial No. 506,622.

This invention relates to that type of material handling mechanism known as a cupola charger.

In charging cupolas the charging material is loaded into buckets having drop bottoms or dump bottoms and the hoisting mechanism picks up these buckets, elevates them and carries them to the cupola. During the travel of the bucket from the place at which it is loaded to the cupola it is imperative that the hoisting mechanism not only support the bucket body but also hold the drop bottom closed so as to retain the material in the bucket. However, when the bucket has entered the cupola, it is desirable to drop the bottom and consequently discharge the contents of the bucket into the cupola.

One of the principal objects of the present invention is to provide a simple, durable, reliable and practical cupola charger adapted for embodiment in any of the various types of crane or traversing hoist constructions ordinarily used to meet the varying conditions in actual practice and which exerts a positive lift on the drop bottom and the bucket body during the hoisting, traveling and lowering and yet is readily operable to lower the drop bottom relative to the bucket body when the bucket is in the cupola whereby to effect dumping or discharge of the contents of the bucket.

Another important object of the present invention resides in the provision of a cupola charger which is so constructed and organized as to employ but a single hoisting drum for both the bucket body and its drop bottom.

A further object of the invention is to provide a cupola charger of this character which is speedy and effective in operation, easily controllable and simple and compact in its construction.

Other objects and advantages reside in

certain novel features of the construction, arrangement and combination of parts which will be hereinafter more fully described and particularly pointed out in the appended claims, reference being had to the accompanying drawings forming a part of this specification, and in which:

Figure 1 is a view partly in side elevation and partly in vertical section showing the cupola charger constructed in accordance with the present invention and embodied in one type of crane construction;

Figure 2 is a view similar to Figure 1 but showing another type of crane construction;

Figure 3 is a fragmentary view partly in side elevation and partly in vertical section showing the cupola charger embodied in a monorail hoist;

Figure 4 is a view in vertical section taken on line 4—4 of Figure 3 with parts shown in elevation for the sake of illustration; and

Figure 5 is a detail sectional view on line 5—5 of Figure 3.

In all of the types of construction illustrated in the drawings, the hoisting mechanism for controlling the raising and lowering of the buckets with its bottom and the means organized therewith for providing for relative movement between the bottom and the body for dumping is the same in all substantial respects. The differences in the various constructions reside merely in the adaptations of this hoisting mechanism and means to the different types of traversing hoists or cranes.

In all embodiments of the invention a bucket 1 is employed and is provided with a separate cone-shaped drop bottom 2 (see Figures 3 and 4). A vertical stem or shaft 3 has its lower end securely fastened as at 4 to the apex portion of the bottom 2. The upper end of the stem 3 is enlarged and slotted as indicated at 5 and is adapted to interengage with a hook 6 suitably connected to a yoke 7 fastened as at 8 to the two parts 9.

of the hoisting line. These parts 9 are reeved over guide pulleys 10 which are carried on the projecting arms 11 (see Figure 1), 12 (see Figure 2), or 13 (see Figure 3) of the 5 frame of the traversing hoist structure and after passing over these guide pulleys the line parts 9 are wrapped around a single drum 14 mounted on the frame of the hoist and controlled and actuated in the conventional manner from an electric motor or any 10 suitable type of motor which is directly geared thereto. The two line parts 9 are utilized to give a balanced suspension to the bucket but of course they function as a single line in the hoisting action and it is to be understood that a single line may be employed is desired.

With the construction as thus far described the motor driven drum 14, when operated, 20 acts through the hoist lines 9 to raise and lower the bucket body 1 and its bottom 2 as a unit. This provides for the lifting up of a loaded bucket from the source of supply of the charging material, and also the lowering 25 of an empty bucket. When, however, the traversing hoist mechanism employed has positioned the loaded bucket in the cupola and it is necessary to lower the bottom 2 while retaining the body 1 against movement to provide for the discharge of the 30 contents of the bucket, it is essential that some means be brought into play for supporting the bucket body independently of the hoist lines 9.

35 For this purpose the present invention proposes a pair of hooks designated at 15 and having elongated shanks 16, the upper ends of which are suitably supported on the hoist structure. The hook portions proper 40 are designed to interengage with suitable cooperable structure on the body 1 of the bucket, as for example, diametrically opposite and outwardly projecting trunnions 18 securely fastened to the body of the bucket 45 adjacent its upper end.

At all times except when the bucket is in the cupola charger ready for dumping the hooks 15 are biased to an idle or inoperative position wherein they are spaced from and 50 out of engagement with the trunnions 18. In this way the hooks do not interfere with the functioning of the hoist mechanism for raising and lowering the bucket body and its bottom simultaneously and as a unit.

55 This biasing means may consist of a spring or weight suitably connected to the hooks and in the present construction comprises a weight 20 carried by the outer end of an arm 21 of a multi-arm lever designated 60 generally at 22. The lever 22 is fulcrumed as at 23 on a suitable stationary part of the traveling hoist and has an arm 24 extending downwardly from the fulcrum and connected in a special manner to one end of a connecting rod structure 25, the other end of the

connecting rod 25 being connected to the hooks 15. In the construction illustrated, wherein the shanks of the hooks are interconnected by an integral cross member 17, it is sufficient to attach the connecting rod to one stem 16 as this provides for simultaneous operation of both hooks. Of course, if the hooks were separate and separately mounted it would be necessary to provide a separate lever 24 and connecting rod 25 for each hook. 70 75

The special connection between the connecting rod 25 and the lever arm 24 is such as to provide a certain amount of yieldability in the actuation of the hooks in one direction and yet provide also for their positive actuation in the other direction. In carrying out this purpose, the lower forked end of the lever arm 24 supports a pivot pin 26 which is formed with a transverse opening 27 through which the end portion 28 of a connecting rod 25 is slidably fitted. On the extreme end of the portion 28 a nut or head 29 is securely fixed so that when the lever arm 24 swings to the right as viewed in Figure 3 a positive pull will be exerted on the connecting rod and applied to the hooks 15 to swing them to the idle or inoperative position indicated by the dotted lines. However, when the lever arm 24 is swung in an opposite direction to bring the hooks into engagement with the trunnions 18 the force exerted through the lever 24 is applied to one end of a coil spring assembly 30 encircling the portion 28 and abutting the pin 26 at one end and a shoulder 31 at its other end. In this way, if the bucket should be turned slightly or if for any reason one hook 15 should strike its trunnion 18 before the other then the resulting shock is taken up by spring assembly 30 and breakage or undue strain avoided. 90 95 100 105

110 For automatically moving the hooks 15 from their idle position shown in dotted lines in Figure 3 to their active position shown in full lines in the same figure, when the bucket is positioned within the cupola and ready for dumping, the lever 22 is provided with a third arm 35 having a replaceable tip part 36 which is designed to engage a stop or abutment 37 so positioned and arranged that as the bucket enters the cupola the engagement of the tip 36 of lever arm 35 with the stop 37 will cause the lever arm 35 and consequently the entire lever structure 22 to rotate in a clock-wise direction as viewed in Figure 3 thereby moving the hooks 15 into engagement with the trunnions. As soon as the hoist structure backs away from the cupola the tip portion 36 of the lever 35 is disengaged from the stop 37 115 120 125 and the biasing means shown as the weight 20 functions to automatically return the hooks 15 to their inactive position.

130 In the type of construction shown in Figure 3, the invention is embodied in a mono-

5 rail system and the arms 13 which carry the hooks 15 and guide pulleys 10 as well as the automatic means for shifting the hooks to operative and inoperative position are
 10 formed as extensions of the frame 40 of the monorail hoist. This frame 40 is supported by hangers 41 and flanged wheels 42 on the monorail track 43. The stop 37 is fastened to the end portion of this monorail track 43
 15 so that as the frame 40 comes to the position wherein the bucket is within the cupola C and ready for dumping the hooks 15 will be rocked into position to be engaged with the trunnions 18 and consequently upon lowering 20 of the lines 9 the bucket body 1 and bottom 2 will descend together until the trunnions 18 are supported in the bills of the hook whereupon further downward movement of the body 1 is prevented and the bottom 2 descends alone to discharge the contents of the bucket.

25 In the type of construction shown in Figure 1, the hoisting mechanism, the hooks and the means for shifting the hooks are all mounted on the frame 50 of a crane designated generally at 51 and of the type having a motor driven traveling bridge 52 which moves transversely with respect to the cupola C. In this construction the stop 37 is
 30 carried or fastened to the traveling bridge 52.

35 In the type of construction shown in Figure 2, the arm 12 is securely fastened to and supported on the traveling truck 55 which rides on the rails 56 of a motor driven traveling bridge 57. In this type of crane construction the bridge 57 moves toward and away from the cupola and the motion of the bridge brings the tip 36 of the lever 35 into engagement with the stop 37 which is carried in this construction by the cupola itself. The motion of the truck 55 moves the bucket transversely with respect to the cupola or cupolas. These various types of crane structures or traversing hoist structures are all old and well known and per se form no part of this invention.

45 The invention claimed is:

1. A cupola charger comprising a bucket having a body, a dump bottom cooperable with the body, hoisting mechanism including a traveling truck having a motor driven hoist drum, a hoisting line controlled by the drum and connected to the bottom of the bucket and operable to raise and lower the bucket body and bottom as a unit, and means carried by and controlled in its action by the position of the truck of the hoisting mechanism and engageable with and disengageable from the body for supporting the body independently of the bottom when desired.

2. A cupola charger comprising a bucket having a body, a dump bottom cooperable with the body, hoisting mechanism including a traveling truck having a motor driven hoist drum, a hoisting line controlled by the

drum and connected to the bottom of the bucket and operable to raise and lower the bucket body and bottom as a unit, hooks carried by the truck, said bucket body having trunnions with which the hooks are engageable, means for causing the hooks to engage the trunnions and to disengage the same at the proper times and consisting of biasing means for shifting the hooks to inactive position wherein they are disengaged from the trunnions, and a cooperable arm and stop for overcoming the action of the biasing means and shifting the hooks into engagement with the trunnions when the bucket is in position for discharging.

3. A cupola charger comprising a bucket having a body, a dump bottom cooperable with the body, hoisting mechanism including a traveling truck having a motor driven hoist drum, a hoisting line controlled by the drum and connected to the bottom of the bucket and operable to raise and lower the bucket body and bottom as a unit, hooks carried by the truck, said bucket body having trunnions with which the hooks are engageable, means for causing the hooks to engage the trunnions and to disengage the same at the proper times, and comprising a multi-armed lever, a one-way yieldable connection between one arm of the lever and the hooks, biasing means coacting with another arm of the lever and a stop engageable with the third arm of the lever when the bucket is in position for discharging.

4. A cupola charger comprising a bucket having a body, a dump bottom cooperable with the body, a hoisting mechanism including a traveling truck having a single motor driven drum, a hoisting line actuated and controlled by the drum and connectible with the bottom of the bucket and operable to raise and lower the bucket body and bottom as a unit, a grapple structure positively and pivotally connected to the truck of the hoisting mechanism and engageable with and disengageable from the body for supporting the body independently of the bottom when desired, means for biasing the grapple structure to inoperative position wherein the bucket body is under the sole control of the hoisting line, and means for shifting the grapple structure to operative position and into supporting relation to the body when the contents of the bucket are to be discharged.

5. A charger for cupolas of the type wherein a part of the structure is stationary comprising a bucket having a body, a drop bottom cooperable with the body, hoist mechanism including a traveling truck having a motor driven drum, a hoisting line actuated and controlled by the drum and connectible to the bottom of the bucket for raising and lowering the bucket body and bottom as a unit, interengageable supporting members between the truck and bucket body, means

for biasing the interengageable supporting members to disengaged positions and cooperating means between the truck and said stationary part of the structure for shifting the interengaging parts into engaged position when the bucket is in position in the cupola for discharging its contents.

6. A cupola charger comprising a bucket having a body, a dump bottom cooperable with the body, hoisting mechanism including a traveling truck having a single motor driven hoist drum, a hoisting line controlled by the drum and connected to the bottom of the bucket and operable to raise and lower the bucket body and bottom as a unit, hooks directly and positively pivoted to the truck, said bucket body having hook engaging means whereby the body may be supported on the hooks and means for shifting the hooks to engaged and disengaged position at the proper times.

7. A cupola charger comprising a bucket having a body, a dump bottom cooperable with the body, hoisting mechanism including a traveling truck having a motor driven hoist drum, a hoisting line controlled by the drum and connected to the bottom of the bucket and operable to raise and lower the bucket body and bottom as a unit, hooks directly and positively pivotally supported on the truck and engageable with and disengageable from the body for supporting the same directly from the truck when desired, and means for shifting the hooks into and out of engagement with the bucket body.

8. A cupola charger comprising a bucket having a body, a dump bottom cooperable with the body, hoisting mechanism including a traveling truck having a motor driven hoist drum, a hoisting line controlled by the drum and connected to the bottom of the bucket and operable to raise and lower the bucket body and bottom as a unit, hooks carried by the truck, said bucket body having hook engaging means cooperable with the hooks to provide for the support of the bucket body directly from the truck, means for biasing the hooks to disengaged position and means including a stationary abutment and a movable part connected to the hooks and engageable with the abutment and moved by virtue of said engagement in a certain position of the truck for automatically shifting the hooks to engaged position when the bucket is in proper position for discharging in the cupola.

9. A cupola charger comprising a bucket having a body, a dump bottom cooperable with the body, hoisting mechanism including a traveling truck having a motor driven hoist drum, a hoisting line controlled by the drum and connected to the bottom of the bucket and operable to raise and lower the bucket body and bottom as a unit, hooks carried by the truck, said bucket body having hook

engaging means cooperable with the hooks to provide for the support of the bucket body directly from the truck, means for biasing the hooks to disengaged position, and a cooperable arm and abutment for overcoming the action of the biasing means and shifting the hooks into engagement with the hook engaging means of the bucket when the bucket is in proper position for discharging in the cupola.

In witness whereof, I hereto affix my signature.

NILS PETER ERIK ANDERSEN.
